Primary Examiner — Cynthia M Chin(74) *Attorney, Agent, or Firm* — Brian J. Teague**CLAIM**

I claim the ornamental design for a device for supporting an object, as shown and described.

DESCRIPTION

This application claims priority to U.S. Design Pat. No. D613,582, filed Dec. 22, 2009 and issued Apr. 13, 2010, and to U.S. Design Pat. No. D609,077, filed Sep. 17, 2009 and issued Feb. 2, 2010, which are divisionals of and claim priority to U.S. Design Pat. No. D603,245, filed Mar. 20, 2009 and issued Nov. 3, 2009; which in turn is a continuation-in-part of and claims priority to U.S. Design Pat. No. D602,341, filed Oct. 20, 2008 and issued Oct. 20, 2009; which in turn is a continuation-in-part of and claims priority to U.S. Design Pat. No. D581,251, filed Aug. 14, 2007 and issued Nov. 25, 2008, and U.S. Design Pat. No. D581,254, filed Sep. 20, 2007 and issued Nov. 25, 2008; the contents of which are incorporated herein by reference in their entirety.

FIG. 1 is a perspective view of one embodiment of a device for supporting an object showing the new design;

FIG. 2 is a front elevational view thereof;

FIG. 3 is a rear elevational view thereof;

FIG. 4 is a top view thereof;

FIG. 5 is a bottom view thereof;

FIG. 6 is a perspective view of an alternative embodiment of a device for supporting an object;

FIG. 7 is a front elevational view thereof;

FIG. 8 is a rear elevational view thereof;

FIG. 9 is a left side elevational view thereof;

FIG. 10 is a right side elevational view thereof;

FIG. 11 is a top view thereof; and,

FIG. 12 is a bottom view thereof.
